UNITED STATES PATENT OFFICE

CHARLES L. STOKES, OF LOS ANGELES, CALIFORNIA, ASSIGNOR TO CURTIS B. CAMP,
TRUSTEE, OF GLENCOE, ILLINOIS

METHOD AND MEANS FOR REGULATING FUEL

Application filed June 12, 1923. Serial No. 644,923.

My invention relates to improvements in automatic carbureting apparatus wherein the operation of priming an internal combustion engine and then cutting off the priming mixture is automatically controlled.

The principal object of my invention is to provide a carburetor wherein the carburetor is automatically primed, and the rate of fuel fed thereto governed.

10 A further object of my invention is to provide automatic priming means whereby a very rich mixture is first fed to the engine for starting, then reduced to a rich mixture until the engine warms up whereupon the 15 priming mixture is automatically cut out, or reduced to that required for normally supplying the engine at a given temperature.

Another object is to provide improved automatic accelerating means to work in co-20 operation with the automatic priming means.

Another object is to embody the automatic priming and accelerating means in a carburetor as a unit.

Another object is to provide automatic 25 fuel regulation for all conditions of engine operation which regulation is governed by the manifold vacuum and temperature of the engine. More specifically stated, the regulation is regulation of increasing and decreasing richness of the mixture by and in 30 accordance with the vacuum in the intake manifold above the throttle conjointly and interdependently with regulation by and in accordance with the temperature of the outgoing jacket water from the engine.

35 Referring to the drawings, in which like numbers indicate the same parts:—

Fig. 1 is a vertical view and part section 40 of a carburetor co-ordinating with automatic priming and accelerating means.

Fig. 2 is a vertical view and part section of the carburetor attached to an internal combustion engine.

45 Fig. 3 is a vertical view and part section of the automatic priming and accelerating means attached to any carburetor.

Fig. 4 shows a vertical view and part section of a preferred modification.

50 Fig. 5 shows a view and part section of

the modification shown in Fig. 4 as applied to an engine.

Fig. 6 is a vertical sectional view of part of Fig. 4.

Fig. 7 is a view along the lines 7—7 of 55 Fig. 4.

With reference to the drawings 1 is the intake manifold of an internal combustion engine to which is attached a carburetor 2 having a choke throat 3, a throttle valve 4, a feed nozzle 5, a float chamber 6, a fuel needle valve 7, a passage 8 connecting the float chamber 6 with 5 and a by-pass 9.

A pipe 10 fits into the carburetor at one end on the engine side of throttle 4 and at the 65 other end is connected to a casing 11 which contains a pressure responsive element 12. The element 12 is held securely at one end in casing 11 by a lock nut 13. The element 12 has a plunger rod 14 fastened to its other 70 end adapted to be guided centrally and having on one end thereof a pump disc 15 on top of which is a check valve 16 cooperating with holes 17 in the disc to control the passage of fuel therethrough.

75 Disc 15 is so constructed as to move freely in a casing 18, the lower part thereof being connected by a pipe 19 to the float chamber 6. The passage of liquid fuel therethrough is governed by a check valve 20 adapted to close 80 a port 21. The upper part of 18 is connected by a passage 22 into by-pass 9.

85 A priming pipe 23 is also connected on the engine side of throttle 4, one end 24 of which is open to atmosphere and has connected thereto a pipe 25 for the purpose of withdrawing waste vapors from a vacuum tank such as is described in my copending application, S. N. 626,990, filed March 22, 1923. The entrance of pipe 23 into carburetor 2 is regulated by the 90 size of an orifice 26 and fuel is fed into pipe 23 from by-pass 9 and governed by the size of an orifice 27. The amount of air which may be fed through pipe 23 may be governed by a port 28 through the center of plunger rod 14 and additional air is provided by an adjusting valve 29 which has holes 30 therein for the purpose of regulating the richness of the mixture supplied to the engine through orifice 26. The amount of fuel, and the time of 100

discharge thereof from casing 18 into by-pass 9 is regulated by the size of orifice 31 at the end of passage 22.

The interior of element 12 is connected by a pipe 33 to a thermostatic bulb 34 fixed in the water jacket 35 of an internal combustion engine 36 to which manifold 1 and carburetor 2 are attached.

The operation of my device, as already described Figs. 1 and 2 is as follows:

If it is assumed that engine 36 is still at a normal temperature, say about 50° F. the position of my priming device will be about as shown in Fig. 1, wherein port 28 would be out of register with pipe 24, and consequently upon cranking engine 36 in order to start the same, throttle 4 being closed, a high vacuum results immediately, being applied through orifice 26 to pipe 23 and orifice 27 whereupon a jet of gasoline will be drawn from by-pass 9 into the engine.

It is understood that throttle 4 controls the mixture of air and gasoline passing into engine 36 through manifold 1, the gasoline in part being supplied through nozzle 5 and the air through 37. Float chamber 6 constitutes a liquid fuel supply for the carburetor 2 and liquid fuel is fed to chamber 6 from the vacuum tank, or by pressure, or by other means well known in the art. Many equivalents of chamber 6 are known and may be substituted therefor, provided an adequate source of liquid fuel supply is available to feed the carburetor 2.

At this time the same vacuum is applied to the interior of casing 11 thus causing the expansion of element 12 downwardly causing the solid stream of gasoline which is drawn through orifice 27 to be reduced in volume owing to the fact that port 28 becomes partly open through registry with the interior of pipe 23 allowing an ingress of air which causes a reduction of vacuum applied to orifice 27. At the same time the downward expansion of element 12 causes disc 15 to be thrust further into the gasoline standing below the liquid level A—A in casing 18 and causes valve 20 to close, thus forcing gasoline through openings 17 to the upper side of disc 15.

By making disc 15 nearly the diameter of casing 18, it will be seen that a dash pot effect ensues by means of which the speed of plunger 14 with opening 28 may be regulated in accordance with any desired result for a particular engine. A similar effect can be produced by making disc 15 of a different diameter and regulating the size of holes 17.

A quick opening of valve 28 is therefore provided for whereby the richness of the mixture supplied through orifice 26 is suddenly reduced, or a delayed opening of valve 28 can be assured for prolonging the supply of a rich mixture through orifice 26. In this connection it will be noted that the shape of port

28 is such as to give an increasing effective area for the passage of air as plunger 14 moves downwardly, 14 being shaped to form a cone-like cross section at 28, and in this manner also the richness of the mixture supplied through orifice 26 may be regulated.

The engine having received a very rich mixture is thereby started. The richness of the mixture immediately is reduced to that required according to the temperature of the motor upon the decrease of pressure in casing 11. If it is assumed that the engine continues to idle the heating of the water in 35 will cause the expansion of a suitable liquid enclosed in bulb 34 whereon the vapor pressure of said liquid will cause a further movement of element 12 and cause a reduction in the fuel supplied through orifice 27 by the further opening of valve 28. Thus an automatic regulation for starting and idling purposes may be supplied through unitary means.

Upon an increase in speed, by the opening of throttle 4, the vacuum applied to orifice 26 will decrease while that applied to the upper part of nozzle 5 will increase whereupon a diminished fuel feed will result through orifice 26 and fuel will commence to feed through nozzle 5, the amount being fed through the nozzle, being governed by needle valve 7 which controls the entrance of liquid fuel from fuel chamber 6 into passage 8.

If it is assumed that the engine is moving slowly under closed throttle and it is desired to suddenly accelerate the engine, upon opening throttle 4 to its fullest extent the vacuum in casing 11 applied to element 12 will suddenly diminish causing element 12 to contract suddenly, thereby causing the fuel on the upper part of disc 15 to be suddenly ejected through orifice 31 into by-pass 9 and thence through nozzle 5, orifices 27 and 26, into mixing chamber of carburetor 2. Thus an accelerating charge will be automatically supplied to the engine which will give it an unusual flexibility.

If the engine is going at high speed, or at full load with wide open throttle, the vacuum on the upper end of nozzle 5 will exceed the vacuum applied through orifice 26, therefore, by suitably arranging the sizes of orifice 26, 27 and 31, it may be so arranged that at any predetermined engine speed, fuel will be supplied to nozzle 5 through passage 8 and orifice 31 because the suction applied to the upper end of nozzle 5 at that speed will be sufficient to shut off the supply of fuel through orifice 27 and draw air therethrough into by-pass 9, thus feeding an emulsion of air and liquid fuel to the engine through 5. This is important because the apparatus may be applied to carburetors for giving a correct mixture at all different speeds.

An adjusting valve 29 is provided, having

air holes 30 therein, for the purpose of regulating the proportion of air and fuel supplied through orifice 26. Valve 29 may be termed the low speed adjustment whereas needle valve 7 may be termed the high speed adjustment.

The liquid contained in bulb 34 may be liquid sulphur dioxide, casing head gasoline, or any liquid suitable for use in thermostatic apparatus or similar design and tube 33 may be a capillary tube.

In Fig. 3 here shown the application of my priming and accelerating device to a carburetor 2 which may have any other means of fuel regulation apart from the design as shown in Fig. 1, and I accomplish this by simply detaching by-pass 9 from passage 8 and coupling the same direct to passage 22 without the intervention of orifice 31. In this manner priming, idling, and accelerating may be accomplished, or I may eliminate the idling feature, and attach my apparatus to any well-known make of carburetor.

In Figs. 4, 5, 6, and 7, I illustrate a preferred modification wherein similar instrumentalities as described are changed to procure a better effect. A fitting 40 is inserted through the wall of the mixing chamber of carburetor 2 and has an end projecting therein containing a relatively large central orifice 41 and a number of smaller orifices 42 for the purpose of aiding in atomizing fuel passing therethrough. A second fitting 38 projects into 40 and is connected interiorly with passage 23, and with passage 22 through a nozzle 43. Air regulating valve 29 is also connected to fitting 38 and a guide pipe 39 effectively directs liquid fuel from nozzle 43, as well as air from passage 23 and valve 29, to be atomized and passed to the engine through orifice 41 and 42.

Within the element 12 is placed a water well 44, held on cover 11^a by a lock nut 45. The top of 44 is tightly closed by a plug 46 through which a water inlet pipe 47 and a water outlet 48 passes. The element 12 may be supplied with any of the volatile liquids already mentioned for generating pressure, or may be filled with gas, or with air.

The end of the inlet pipe 47 is connected to the water jacket 35 and has its inner end turned to receive water under the pressure by which it is circulated through water jacket 35 by the water pump 49. The end of water inlet 48 is placed to join the water system on the suction side of pump 49 and has its inner end turned to discharge water from 44 conformably with the stream of water being drawn into the pump. In this manner the temperature of the engine is transferred to element 12 for partly and relatively governing its movements.

The time for causing a movement of element 12 may also be governed by the size of

passage 10, and at times I have found it advantageous to place in 10 a check valve which has only a very small opening therethrough when high vacuum is applied to 10, but which is fully opened when low vacuum is applied to 10.

Also at times it is advantageous to place a check valve in passage 22 in order to permit a one-way flow of liquid fuel from casing 18 to the engine, but all such accessories will be apparent to those skilled in the art.

It will thus be seen that by simple and automatic means, I am enabled to supply the engine with a sufficiently rich mixture of gasoline to not only start the same but continue the same in operation and govern the amount of fuel fed thereto in correct proportions according to the temperature of the engine. Furthermore, I am enabled to not only start an engine but I am enabled to take a motor car in which the engine may be started and immediately get under way with the same without any delay, whether acceleration be immediately required or not.

The present common arrangements of starting an engine is to cut off the supply of air thereto, whereby a very rich mixture is drawn through the carburetor nozzle, but this method is open to a great many objections because at times the mixture fed to the engine is too rich to start and at other times is too lean to start, but in either case, during very cold weather, the choker has to be manipulated by hand giving very unsatisfactory results especially if traffic is heavy, or it is desired to move rapidly. In addition to this crank case dilution takes place and by my herein described apparatus I can substantially eliminate the above defects no matter what the temperature may be.

I claim:—

1. The method of supplying fuel to an internal combustion engine which consists in applying the engine vacuum and pressures varied by and in accordance with the engine temperature to a pressure responsive element, supplying an excess of fuel to start the engine, reducing the amount of excess fuel suddenly and then gradually after the engine is started, and feeding an excess of fuel to the engine upon the reduction of vacuum applied to the pressure responsive element.

2. The combination with an internal combustion engine, of a manifold, a carburetor attached to said manifold, a liquid fuel chamber, means to feed liquid fuel from said chamber to said carburetor, a casing attached to said carburetor, and means controlled conjointly by and in accordance with both the vacuum and temperature of the engine for automatically supplying the engine with excess fuel through said casing for starting and accelerating.

3. An internal combustion engine having a water jacket, a manifold, a carburetor at

tached to the manifold, a liquid fuel chamber feeding the carburetor in combination with means controlled by the engine vacuum and by the engine temperature for automatically supplying the engine with excess fuel for starting and accelerating; said means including a pipe for feeding fuel to the manifold, and a thermostatic connection to the water jacket.

10 4. An internal combustion engine having a water jacket, a manifold, a carburetor attached to the manifold, and means for supplying liquid fuel and air to the carburetor, in combination with means for supplying excess fuel; said means including a valve and a pressure responsive device for operating it and means for applying to the latter pressures derived from the intake between the throttle and the engine and pressures varying by and in accordance with internal temperatures of the engine.

15 5. An internal combustion engine having a water jacket, a manifold, a carburetor attached to the manifold, and means for supplying liquid fuel and air to the carburetor, in combination with means for supplying excess fuel; said means including a valve and a pressure responsive device for operating it and means for separately but simultaneously applying to the latter pressures derived from the intake between the throttle and the engine and pressures varying by and in accordance with internal temperatures of the engine.

20 6. An internal combustion engine having a water jacket, a manifold, a carburetor attached to the manifold, and means for supplying liquid fuel and air to the carburetor, in combination with means for supplying excess fuel; said means including a valve and a pressure responsive device for operating it and means for applying to the latter pressures varied by and in accordance with the vacuum in the intake, between the throttle and the engine, and by and in accordance with internal temperatures of the engine.

25 7. An internal combustion engine having a water jacket, a manifold, a carburetor attached to the manifold, and means for supplying liquid fuel and air to the carburetor, in combination with means for supplying excess fuel to the carburetor mixture; said means including a valve and a pressure responsive device for operating it, means for operating the latter by applying varying vacuum thereto, and means for automatically varying the supply of said air in accordance with the movement of said pressure device.

30 8. An internal combustion engine having a water jacket, a manifold, a carburetor attached to the manifold, and means for supplying liquid fuel and air to the carburetor, in combination with means for supplying excess fuel to the carburetor mixture; said means including a valve and a pressure responsive bellows device for operating it and

means for operating the latter by applying varying vacuum pressures derived from the intake between the throttle and the engine and also pressures varying by and in accordance with internal temperatures of the engine.

35 9. An internal combustion engine having a water jacket, a manifold, a carburetor attached to the manifold, and means for supplying liquid fuel and air to the carburetor, in combination with means for supplying excess fuel to the carburetor mixture; said means including a valve and a pressure responsive device for operating it and means for operating the latter by applying varying vacuum pressures derived from the intake between the throttle and the engine and also pressures varying by and in accordance with internal temperatures of the engine.

40 10. An internal combustion engine having a water jacket, a manifold, a carburetor attached to the manifold, and means for supplying liquid fuel and air to the carburetor, in combination with means for supplying excess fuel to the carburetor mixture; said means including a valve and a pressure responsive device for operating it and means for operating the latter by applying varying vacuum pressures derived from the intake between the throttle and the engine and also pressures varying by and in accordance with internal temperatures of the engine, the vacuum pressures being applied externally and the temperature pressures internally of the pressure responsive device.

45 11. An internal combustion engine having a water jacket, a manifold, a carburetor attached to the manifold, and means for supplying liquid fuel and air to the carburetor, in combination with means for supplying excess fuel, said means including a supplemental air and fuel injector discharging into the intake above the throttle, a valve for variably cutting off the supplemental air and means for opening said valve by and in accordance with suction applied from the intake manifold.

50 12. An internal combustion engine having a water jacket, a manifold, a carburetor attached to the manifold, and means for supplying liquid fuel and air to the carburetor, in combination with means for supplying excess fuel, said means including a supplemental air and fuel injector discharging into the intake above the throttle, a valve for variably cutting off the supplemental air and means for opening said valve by and in accordance with suction applied from the intake manifold conjointly with pressures varying by and in accordance with internal temperatures of the engine.

55 13. An internal combustion engine having a water jacket, a manifold, a carburetor attached to the manifold, and means for supplying liquid fuel and air to the carburetor, in combination with means for supplying

- excess fuel, said means including a supplemental air and fuel injector discharging into the intake above the throttle, a valve for variably cutting off the supplemental air and means for opening said valve by and in accordance with suction applied from the intake manifold conjointly with pressures varying by and in accordance with internal temperatures of the engine, said means including a pressure responsive device. 10
14. An internal combustion engine having a water jacket, a manifold, a carburetor attached to the manifold, and means for supplying liquid fuel and air to the carburetor, in combination with means for supplying excess fuel, said means including a supplemental air and fuel injector discharging into the intake above the throttle, a valve for variably cutting off the supplemental air and means for opening said valve by and in accordance with suction applied from the intake manifold conjointly with pressures varying by and in accordance with internal temperatures of the engine, said means including a pressure responsive device having the suction and pressure applied, one externally and the other internally, to operate the pressure responsive device either conjointly or differentially, according to conditions. 20
15. The method of varying the richness of the primary mixture supplied to an internal combustion engine, which method consists in applying pressures derived from and corresponding to the vacuum in the intake manifold and separately therefrom pressures derived from and corresponding to temperatures of the engine to act conjointly or differentially according to conditions, to produce corresponding varied resultant motions of a pressure responsive element and utilizing said resultant motion to control appropriately varied supplies of excess fuel to the primary mixture. 30
16. In combination, a manifold, a carburetor comprising a nozzle, a throttle, means for supplying liquid fuel to said nozzle when said throttle is open, and auxiliary means for supplying fuel to said manifold when said throttle is closed, and for supplying a mixture of fuel and air to said nozzle when said throttle is open. 40
17. In an internal combustion engine, an intake manifold, a throttle in said manifold, a carburetor for supplying an explosive mixture to said manifold, auxiliary means for supplying fuel to said manifold independently of said carburetor, and means operated by the combined action of the suction of the engine and by the heat derived from the engine explosions for controlling the operation of said auxiliary means. 50
18. In combination, an internal combustion engine, an intake manifold therefor, means for supplying an explosive mixture of vary-
- ing richness to said manifold to meet the different engine requirements, said means comprising a pressure responsive element controlled by the combined action of the pressures derived from the suction and heat of the engine. 70
19. A carburetor for internal combustion engines comprising a mixing chamber, means including a thermostatic element for supplying an explosive mixture of varying richness to said mixing chamber to meet varying engine requirements, said element being responsive to the resultant action of changes in temperature and engine suction. 75
